UNITED STATES PATENT OFFICE.

FRED E. SHUTT AND MARCUS H. RINEHART, OF MOUNT LIBERTY, OHIO.

WRECKING CRANE.

Application filed March 2, 1925. Serial No. 12,697.

To all whom it may concern:

Be it known that we, FRED E. SHUTT and MARCUS H. RINEHART, citizens of the United States, residing at Mount Liberty, in the county of Knox and State of Ohio, have invented new and useful Improvements in Wrecking Cranes, of which the following is a specification.

This invention relates to an improved 10 wrecking crane for motor vehicles, the general object of the invention being to provide a crane adapted to be placed on a motor vehicle and having two sets of winding means thereon for operating cables for picking up 15 wrecked motor vehicles and the like.

Another object of the invention is to make the boom part of the device with several sets of pulley holding means so that the pulleys can be placed in the most advantageous 20 position according to the work to be done.

A further object of the invention is to provide means whereby one set of cable operating means can be driven by worm means when desired.

25 This invention also consists in certain other features of construction and in the combination and arrangement of the several parts, to be hereinafter fully described, illustrated in the accompanying drawings and 30 specifically pointed out in the appended claims.

In describing our invention in detail, reference will be had to the accompanying drawings wherein like characters denote like or corresponding parts through out the several views, and in which:—

Figure 1 is a side view of the improvement.

Figure 2 is a plan view thereof.

40 Figure 3 is a longitudinal sectional view through the upper portion of the device.

Figure 4 is a section on line 4—4 of Figure 1.

In these views, I indicates a supporting 45 frame which is adapted to be placed on a platform 2 or other part supported by the motor vehicle. This frame carries a boom 3 which is composed of two parallel beams 4 which are bolted together by the bolts 5 and 50 which are held in spaced relation by the sleeves 6 on the bolts. This boom extends upwardly and forwardly at an angle and carries cross bars 7 at its upper portion, each bar having its ends extending beyond the

55 the beams with the extended portions hooked, as shown at 8. These hooked portions

are adapted to support pulleys, such as shown at 9. An upper drum 10 is mounted on a shaft 11 at the top of the frame and said shaft 11 is connected by the gears 12 with a shaft 13 journaled in the top of the frame and having one end squared, as at 14, to receive a crank handle, such as shown at 15, so that the drum can be rotated by hand 60 so as to wind thereon a cable 16 which is passed through a pulley 9 and which may have a hook 17 fastened to its free end. A lower drum 18 is fastened to a shaft 19 which is journaled in the frame adjacent the vertical center thereof and this shaft 19 is connected by the gears 20 with a shaft 21 which has one end provided with a squared part 22 to receive the crank handle and which also has a worm gear 23 thereon for meshing with a worm 24 on a shaft 25 which is slidably and 70 rotatably supported by the bearings 26 arranged on one side of the frame. This shaft also has a squared end for receiving the crank handle 15. By moving the shaft 25 longitudinally the worm 24 can be moved 75 out of engagement with the worm gear 23 so that the shaft 21 can be rotated by the crank handle but when a heavy load is to be lifted the shaft 25 is moved to place the worm 24 in mesh with the worm gear 23 so that the 80 leg can be lifted through the worm gear.

From the foregoing it will be seen that we have provided a large winch and a small winch, the small winch being operated through a crank handle while the large one 85 is operated through either the crank handle or the worm gearing. If the wrecked car being lifted should need steadyng a cable can be placed on the top winch and fastened to the wrecked car to keep it in an upright 90 position while the large winch is used in moving the car. The cable on the top winch can also be used as a guy wire by fastening it to a tree, pole or the like and in this case the wire will be high enough up as not to hinder traffic. When great power is not needed the worm device can be used as a 95 lock.

As will be seen this device is of simple 100 construction so that it can be manufactured to sell at low cost, it is of light weight and will lift heavy loads with ease. One man can operate both winches and it takes little space in the service car. It also has great boom 105 clearance.

110 It is thought from the foregoing description that the advantages and novel features

of our invention will be readily apparent. We desire it to be understood that we may make changes in the construction and in the combination and arrangement of the several parts, provided that such changes fall within the scope of the appended claims.

What we claim is:—

1. A crane of the class described comprising an upright frame, a stationary boom supported by the frame, a light winch on the top of the frame, a heavy winch supported at the lower part of the frame, a crank handle for turning either winch and a number of pulley supporting means on the boom.
- 10
2. A crane of the class described comprising a supporting frame, a stationary boom supported thereby, a light winch at the top of the frame, a heavy winch at the lower part of the frame, a crank handle for operat-
- 20

ing either winch, a slideable shaft journaled in the frame, a worm thereon, a worm gear on one of the shafts of the heavy winch with which the worm is adapted to mesh when its shaft is moved in one direction, means for permitting the worm shaft to be operated by the crank handle, and pulley supporting means on the boom.

3. A crane of the class described comprising a supporting frame, a boom supported thereby, a number of transverse shafts on the boom having their ends projecting beyond the boom, hooks formed on the said projecting ends for receiving pulleys and a winch supported by the frame.

In testimony whereof we affix our signatures.

FRED E. SHUTT.
MARCUS H. RINEHART.
